ABSTRACT

A chain of series-connected spark gap piles have two grading chains in parallel therewith with connections therebetween. An arrangement is provided for triggering one of the spark gap piles. When this pile is triggered, all the spark gap piles in the chain spark over if the voltage over the spark gap piles between two connections from a grading chain is not less than the spark-over voltage for each of these piles. One grading chain is formed of a number of resistors and capacitors in parallel connected across each end gap pile and each pair of other gap piles, and the other grading chain is formed of resistors in the chain between the pairs of gap piles and circuits formed of a capacitor and a resistor in parallel with each pair of gap piles.

A TRIGGERING CIRCUIT FOR TRIGGERING SERIES-CONNECTED SPARK GAPS

This application is a continuation of application Ser. No. 801,639 filed Feb. 24, 1969 and is now abandoned.

BACKGROUND OF THE INVENTION

Field of the Invention

For various purposes, for example with certain types of over-voltage protection devices, it may be valuable for series-connected spark gap piles to spark over for a voltage which is lower than the total normal spark over-voltage of the series-connected gap piles.

SUMMARY OF THE INVENTION

The present invention relates to a means for triggering series-connected spark gap piles so that by triggering one of the gap piles the entire spark gap chain can be made to spark over—for a voltage which is greater than or equal to half the spark over-voltage for the whole gap arrangement.

BRIEF DESCRIPTION OF THE DRAWINGS

The accompanying drawing shows one example of a system according to the invention.

DESCRIPTION OF THE PREFERRED EMBODIMENTS

The arrangement shown in the drawing consists of a spark gap chain and a first and second grading chain. The spark gap chain consists of a number of series-connected spark gap stack piles G which are preferably equal and have the same spark over-voltage. Resistors R_3 are connected at certain points in the chain. In the shown embodiment of the invention such a resistor is connected between the two outermost gap piles at both ends of the chain, whereas otherwise groups of two series-connected gap piles are separated by one resistor. The resistance of the resistors may vary and can even attain the value zero. It may also vary from resistor to resistor.

The first grading chain consists of a series connection of the resistors R_3 in the spark gap chain and also a number of parallel circuits each consisting of a capacitor and a resistor. The grading chain has one such parallel circuit at each end consisting of a capacitor $2C_1$ and a resistor $R_{one-half}$.

The other parallel circuits consist of a capacitor C_1 and a resistor R_1 . The two outer parallel circuits are connected over a single spark gap pile G whereas all the other parallel circuits are connected over two series-connected spark gap piles.

The second grading chain consists of a number of series-connected parallel circuits, each consisting of a capacitor C_2 and a resistor R_2 . Each of these circuits is connected over a resistor R_3 and a spark gap G situated on each side of the resistor in the spark gap chain. Alternatively the central point of a resistor R_1 in the first grading chain may be connected to the connection point of the spark gap chain on the second grading chain. In such an arrangement the resistor R_2 in the second grading chain can be omitted.

The two grading chains control the voltage over the spark gap chain both capacitively and resistively. Regarding the size relationship between the resistors R_1 and R_3 which are in series with each other, it should be mentioned that R_1 is very much larger than R_3 and that the latter may even be zero.

Over one or more of the spark gap piles in the spark gap chain a triggering circuit T is connected, with the help of which the spark gap piles connected to the triggering circuit

can be ignited. In the drawing the triggering circuit is shown connected to the lowermost spark gap pile which, from the point of view of insulation, is most advantageous. The triggering circuit consists of a voltage source B , a resistor R and a switch S .

If the voltage over the whole chain is U , this means that each of the capacitors C_1 and C_2 is charged to a voltage $2U/n$ where n is the number of series-connected spark gap piles. By supplying a triggering pulse to one or more of the gap piles, for example the lowest, so that it sparks over, all the voltage over the lowermost capacitor C_2 will then be situated over the second gap pile from below so that the voltage over this gap pile is doubled and becomes equal to $2U/n$. If U is sufficiently high, greater than or equal to half the spark over-voltage for the series-connected gap piles, the second gap pile from below will spark over immediately after the lowermost gap pile has sparked over. When the second gap pile has sparked over the third from below receives a voltage $2U/n$ and sparks over. In this way the gap piles spark over successively upwards. The through-ignition time, that is the time from when the lowermost gap pile is triggered until the entire chain has sparked over, depends first on the construction of the gap pile since the capacitor C_1 in a circuit must be discharged before further gap piles can be ignited. The size of R_3 , however, is of no importance for the through-ignition time. A resistor R_3 which is more high ohmic has, however, the advantage that the voltage distribution over the chain during the through-ignition process will be more linear.

With an arrangement according to the invention it is possible to build an over-voltage protection device having through-running, parallel legs in which the legs can be ignited successively with the required delay by taking the triggering pulse for a certain leg from a leg which has already sparked over.

What is claimed is:

35. 1. A surge diverter comprising a chain of series-connected spark gap piles, first and second grading chains connected in parallel with said spark gap pile chain, each grading chain comprising a plurality of series-connected circuits, each of said circuits comprising a resistor and a capacitor in parallel-connection, each of said circuits, except the ones at the top and the bottom, in the first grading chain being connected across two spark gap piles in the spark gap pile chain, the connection points for the first and the second grading chains being equally and alternately distributed along the spark gap pile, said connection points constituting the only connections between each grading chain and the spark gap pile chain, a trigger circuit in the first grading chain connected across at least one spark gap pile, which forms a trigger spark gap pile, said trigger spark gap pile being in series with at least one further spark gap pile forming the part of the spark gap pile chain situated between two adjacent connection points for the second grading chain.
45. 2. A surge diverter according to claim 1, in which the spark gap pile chain also includes a number of resistors, evenly distributed within the spark gap pile chain.
55. 3. A surge diverter according to claim 1, in which the circuits of the first grading chain are series-connected with a number of resistors which are connected in the spark gap pile chain, each one between two connection points for said first grading chain.
60. 4. A surge diverter according to claim 1, in which each circuit of the second grading chain is connected in parallel with two spark gap piles and a resistor situated between said two gap piles.
